UNITED STATES PATENT OFFICE.

AUGUST DLOUHY, OF WALLINGFORD, CONNECTICUT, ASSIGNOR TO H. L. JUDD CO.,
OF NEW YORK, N. Y., A CORPORATION OF DELAWARE.

DESIGN FOR A CURTAIN-POLE END.

Application filed May 13, 1926. Serial No. 17,707. Term of patent 3½ years.

To all whom it may concern:

Be it known that I, AUGUST DLOUHY, a citizen of the United States of America, and a resident of Wallingford, in the county of New Haven and State of Connecticut, United States of America, have invented a new, original, and ornamental Design for a Curtain-Pole End, of which the following is a specification, reference being had to

the accompanying drawing, forming part thereof.

Figure 1 is a side elevation of a curtain-pole end embodying my design;

Figure 2 is a side edge view thereof.

I claim:

The ornamental design for a curtain-pole end, as shown.

AUGUST DLOUHY.
